UNITED STATES PATENT OFFICE.

ALFRED ATKINSON, OF JOLIET, ILLINOIS.

FIGURE TOY.

SPECIFICATION forming part of Letters Patent No. 772,492, dated October 18, 1904.

Application filed April 9, 1904. Serial No. 202,393. (No model.)

To all whom it may concern:

Be it known that I, ALFRED ATKINSON, a citizen of the United States, residing at Joliet, in the county of Will and State of Illinois, 5 have invented certain new and useful Improvements in Figure Toys; and I do declare the following to be a full, clear, and exact description of the invention, such as will enable others skilled in the art to which it appertains to make 10 and use the same, reference being had to the accompanying drawings, and to the letters of reference marked thereon, which form a part of this specification.

This invention relates to new and useful 15 improvements in toys; and the object of the invention is to produce a figure toy mounted upon an aerial cycle and so arranged that it will travel upon a cord fastened at one end to a fixed object and having a weight adapted to 20 hold the wheel upon the cord.

The invention consists, further, in various 25 details of construction and combinations and arrangements of parts, which will be herein-after fully described and then specifically defined in the appended claim.

My invention is illustrated in the accompanying drawings, which, with the letters of reference marked thereon, form a part of this application, and in which—

30 Figure 1 is a side elevation of my improved figure toy shown as resting upon a cord, and Fig. 2 is a front elevation of the toy.

Reference now being had to the details of the drawings by letter, A designates a grooved 35 wheel having a crank-shaft B mounted therein, and C designates a wire which is bent upon itself, forming two pieces, which are turned to form eyes E, in which the crank-shaft has bearing. Said wires form the head of the 40 cycle, and the upper portions are twisted together, as at F, and the ends outwardly bent, forming handle-bars G, to which the arms K, pivoted to the body K', are fastened.

N designates bars connected at their lower 45 ends to the shaft B, and their upper ends are fastened to a pin N', passing through the body of the figure K', and the legs M of the figure are pivoted to the body, and the feet have pivotal connection at Q with the cranks of said

shaft and so arranged that as the wheel rotates the legs will be given the natural movement of the legs of an operator driving a shaft by means of pedal and crank-shaft.

The wire C is twisted together at C' and is bent to form a loop O, in which a hook P is 55 adapted to engage, which hook is fastened to a weight W, provided for the purpose of holding the grooved wheel upon a cord R. One end of the cord R is adapted to be fastened to a fixed object at a suitable height—say four 60 or five feet from the floor—and the other end may be held in the hand of an operator, and by the provision of the weight the figure toy will be caused to assume by gravity the lowest position upon the cord. As one end of 65 the cord is raised the toy will be caused by gravity to run down the incline to the lowest portion thereof, and by raising and lowering one end of the cord the toy may be caused to go back and forth thereon.

70 While I have shown a particular detailed construction of apparatus embodying the features of my invention, it will be understood that I may make alterations, if desired, in the construction of the same without in any way departing from the spirit of the invention.

Having thus fully described my invention, what I claim as new, and desire to secure by Letters Patent, is—

80 A figure toy comprising a cycle-frame made of a single piece of wire which is bent to form eyes E, E, a crank-shaft journaled in said eyes, a figure having feet pivotally connected to the cranks of said shaft, and arms connected to the ends of the wire forming the handles of 85 the cycle, the wire forming the lower portion of the frame twisted together and bent to form an eye, and a weight engaging the latter, a grooved wheel fixed to said shaft, and a cord upon which the same is mounted, as 90 shown and described.

In testimony whereof I hereunto affix my signature in presence of two witnesses.

ALFRED ATKINSON.
